UNITED STATES PATENT OFFICE.

ELMER E. WICKERSHAM, OF STOCKTON, CALIFORNIA, ASSIGNOR TO THE HOLT MANUFACTURING COMPANY, OF STOCKTON, CALIFORNIA, A CORPORATION OF CALIFORNIA.

TRACTOR.

Application filed May 26, 1920. Serial No. 384,344.

To all whom it may concern:

Be it known that I, ELMER E. WICKERSHAM, a citizen of the United States, and a resident of Stockton, county of San Joaquin, and State of California, have invented certain new and useful Improvements in Tractors, of which the following is a specification.

This invention relates to tractors and more particularly to that type of tractors having endless traveling tracks or tread members.

Tractors of the endless belt type usually involve side frames mounted to oscillate vertically on the sides of the main frame of the tractor and ordinarily spring cushioned means are interposed between the oscillating side frames and the main frame of the vehicle to form a yielding action as between the main frame and the side tracks and their frames.

In the above form of construction there is no equalization of the load of the vehicle upon the side frames and their belts or treads and the tractors are not efficiently operative over side hills or uneven roadways for the reason that one or the other of the side belts or tracks will be subjected to the greater portion of the weight of the vehicle.

It is one of the objects of the present invention to improve the construction of the above general character of tractors so that they can be efficiently operated on side hills and so that the load will be equalized or compensated.

A further object of the invention is to provide a simple, substantial, efficient and practicable and compensating device directly connecting the side frames so as to equalize the load of the frame carried by the interposed compensating means.

The invention possesses other objects and features of advantage, some of which, with the foregoing, will be set forth in the following description of the preferred form of my invention which is illustrated in the drawings accompanying and forming part of the specification. It is to be understood that I do not limit myself to the showing made by the said drawings and description, as I may adopt variations of the preferred form within the scope of my invention as set forth in the claims.

Referring to the drawings:

Figure 1 is a side elevation showing conventionally one form of tractor to which the invention is applied.

Figure 2 is a transverse section showing the main frame and the connected side track frames in a normal or horizontal running position when traveling on a level surface.

Figure 3 is a similar section showing the action of the side frames with their tracks when the vehicle is operating over an uneven surface.

The invention is shown as combined with a form of tractor having a main frame 2, with a suitable motor 3 at its front portion, and at the rear end of the frame there is provided a transverse axle or shaft 4 to which power is transmitted by a suitable mechanism not necessary to be here described as it forms no part of the present improvement. The front end of the frame is supported on a steering or caster wheel 5 operatively connected to the manual steering wheel 6 shown as arranged on the rear end of the tractor frame adjacent to the driver's seat.

On the outer end of the rear axle or shaft 4 at each side of the main frame there is provided a suitably shaped and constructed track or tread bearing frame 10 over the periphery of which there travels respective endless belt or tread members 11 constructed and arranged to be engaged and driven by the respective sprocket wheels 12 of which there is one on each end of the shaft 4 and which sprocket wheels 12 are driven by respective pinions 13 forming a part of the drive mechanism of the tractor.

The perimeter of the frame 10 of each belt or tread is shown as provided with races 14, and in opposition to these races 14 there are provided on the inner surface of the elements, constituting the endless track or tread, co-ordinate ball races 15 and between the ball races 14 and 15 there are arranged sets of anti-friction bearings or balls 16. However it is to be understood that the present invention is not to be limited to use in connection with ball-bearing treads or tracks as it is equally efficient with other types of mountings of endless traveling belts for tractors.

It has heretofore been the practice in the construction of tractors with a pivoted

side frame carrying a traction belt or tread to transmit a part of the load of the vehicle frame to the frames by means of resilient cushions interposed between the main frame and side swinging frames but it is well known that this does not effectively equalize or distribute the weight of the load to the traction belt and it is to that end that the present invention is evolved and provides means for equalizing or compensating the load on the traction members irrespective of the oscillations of the side frames, and one form of such compensating means is described with respect to the illustrated embodiment of the invention.

As shown in Figure 1, the rear ends of the side frames 10, are pivotally mounted on the outer ends of the axle 4 and the forwardly extending portions of each of the side frames are designed to oscillate vertically in accordance with obstructions or the undulations of the surface over which the vehicle may be traveling.

In the present invention the forward swinging ends of each of the side frames are effectively connected together by suitable means so that when there is a tendency of one of the side frames to swing upwardly on its pivot, a part of the increased load to which the upwardly swinging frame is subjected is transmitted by the connecting means to the opposite side frame and therefore the load is equalized at all times during the operation of the tractor.

Though such transversely extending connecting means may be of any suitable type of construction and arrangement it is shown in Figures 2 and 3 as comprising a substantial, flexible element in the form of a sprocket chain 20 passing transversely below the body or main frame 2, and thence outwardly and upwardly with the ends connected as at 21 to suitable parts 22 provided on the upper portions of each of the side frames 10 and from this it will be seen that a tendency of upward movement of one of the frames results in a downward pulling movement in the opposite frame due to the transverse connecting means. Weight of the frame 2 and its load is transmitted to the transverse member 20 which constitutes therefore, substantially, a carrier or saddle and it is shown as engaging suitable guide-means here constituting idler wheels or sprockets 23 provided in suitable bearings or downwardly extending brackets 24 below the side members of the main frame 2 and at such positions as to permit the outwardly and upwardly extending ends of the sprocket chain 20 to freely run upwardly and downwardly and in either direction across the width of the frame.

The journals of the sprocket wheels or guide rollers 23 may be yieldingly supported

with respect to the frame 2 or rigidly as desired but in either event the load subjected to the saddle forming member 20 would be equally transmitted to the side traction carrying frames 10.

In Figure 2 the side frames with the main frame 2 are shown as resting upon a substantially flat or horizontal surface with the bottom portions of the tread belt resting upon a substantially even plane and in this view the brackets 24 in which the wheels 23 are provided are shown as rigidly connected to the main frame 2. In Figure 3 the vehicle is shown as disposed and operating over an inclined surface with the result that one of the side frames 10 is in an elevated position while the opposite side frame is depressed relatively thereto and clearly showing how the load is transmitted by the connecting saddle forming part 20 equally to the side bearing members 10. In Figure 3 the parts 24 in which the idler or guide wheels 23 are arranged are shown as yieldingly connected to the main frame 2.

The yielding action of the brackets 24 of Figure 3 may be secured as by springs 25 arranged between the frame 2 and the brackets 24 which are pivoted as at 26 to the frame.

It is understood that the parts may be variously arranged, constructed and formed in the adaptation of the invention to a given structure within the spirit of my invention and the scope of the appended claims.

I claim:

1. In a tractor, a main frame, a self-laying track unit at each side thereof, including a truck frame pivotally connected to the main frame for rocking movement in a vertical plane, and an equalizing suspension means between each truck frame and the main frame, comprising a flexible member connected to opposite truck frames and passing slidably beneath the main frame.

2. The combination set forth in claim 1, including anti-friction devices on the main frame against which the flexible member operates.

3. The combination set forth in claim 1, including anti-friction devices on the main frame under which the flexible member passes, and springs interposed between the anti-friction devices and the main frame.

4. In a tractor, a main frame, a self-laying track unit at each side thereof, including a truck frame pivotally connected at its rear end to the main frame for rocking movement in a vertical plane, and a chain connected to opposite truck frames at the forward ends of the latter passing slidably beneath the main frame for suspending the weight of the latter equally upon the truck frames.

5. In a vehicle of the self-laying track

type including a body or frame and a truck mechanism pivotally connected thereto at each side for rocking movement in a vertical plane, equalizing suspension means comprising a flexible member connected at its ends to the truck mechanisms and slidably engaging the body or frame.

In testimony whereof I have hereunto set my hand in the presence of two subscribing witnesses.

ELMER E. WICKERSHAM.
